FRANCOIS VATHÉ, OF NEW YORK, N. Y.

DESIGN FOR A DOLL.

60,076.

Specification for Design.

Patented Dec. 20, 1921.

Application filed August 12, 1921. Serial No. 491,658. Term of patent 7 years.

To all whom it may concern:

Be it known that I, FRANCOIS VATHÉ, a citizen of the United States, and a resident of the city of New York, in the borough of Manhattan and State of New York, have invented a new, original, and ornamental Design for a Doll, of which the following is a specification, reference being had to the accompanying drawings, forming part thereof.

The figure is a front elevation of a doll embodying my new design.

The essential feature of my design consists in the general outline of the doll, which embodies a short body portion having a head, and greatly elongated, unshaped, jointless, flexible arms and legs.

I claim:

The ornamental design for a doll, as shown and described.

FRANCOIS VATHÉ.
